(57) **CLAIM**

The ornamental design for a display screen or portion thereof with icon, substantially as shown or described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. FIG. 1 is a front view of a display screen or portion thereof with icon; and, FIG. 2 is a second embodiment thereof. The broken line showing a display screen in both drawing figures forms no part of the claimed design.
